UNITED STATES PATENT OFFICE.

FREDERICK W. BACORN, OF BUTTE, MONTANA.

LATHERING DEVICE.

Application filed April 11, 1925. Serial No. 22,411.

This invention relates to certain new and useful improvements in lathering devices, and it has for its objects among others to provide a simple, cheap, improved lathering device or brush adapted for this purpose designed for use once and then thrown away. I make a brush, consisting broadly of a base or support for the fibrous member, and a saponaceous substance, embodied in or applied to the fibrous member.

The ordinary shaving brush is composed essentially of stiff but flexible bristles, bound together at one end, with the other end left free, so that in use the bristles move with relation to each other, and when pressed against the face spread out and spring back together again. Generally, after application of the soap to the face, the lather has to be rubbed in with the hands. I propose to avoid all this. My improved soap applicator embodies practically a combined shaving brush, cup, soap, and means of rubbing the lather into the beard, all in a single article. While designed for but one using it can of course be used a number of times, as long as the saponaceous material lasts, but it can be made and placed upon the market at such trifling cost that one can afford to use it but once and then throw it away and take another when again shaving. This applies not only to the individual who shaves himself, but equally as well to use in the barber shop, where one would gladly pay a few cents more to have an individual brush.

By my invention bristles are dispensed with. The hairs or fibres corresponding to the bristles are relatively short, and are combined together in the form of a fabric, which may be knitted, braided or woven, but which is designed to be pressed against the face in a substantially flat or substantially flattened form. It is always ready for use, all that is necessary is to dip it in water and rub it on the face, when a most satisfactory lather is produced. Being practically flat, as the lather is produced it is also at the same time rubbed well into the beard, without any danger of getting the lather on the hands of the user.

Other objects and advantages of the invention will hereinafter appear, and the novel features thereof will be specifically defined by the appended claims.

The invention is capable of embodiment in a variety of forms, some of the most practicable of which, only, are herein illustrated,

but which will be sufficient for a clear understanding of the generic principle of my invention.

The invention, in such embodiments, is clearly illustrated in the accompanying drawings, which, with the numerals of reference marked thereon, form a part of this specification, and in which—

Figure 1 is a side elevation of a shaving brush embodying one form of the invention.

Figure 2 is a plan view of the same.

Figure 3 is a side elevation of another form.

Like numerals of reference indicate like parts throughout the several views.

In carrying out my invention I take a back member 1 which may be a flat piece of wood of sufficient strength, but not necessarily rigid, in fact, it may be best to provide a slight amount of flexibility therein. 2 designates a handle extension which may be used upon the end of the back member 1 if desired.

3 is a piece of material, fabric, wool, or, in some instances, other materials may be employed. I may employ cotton cloth, although I have found that better results are attained by the use of knitted woolen yarn, and if this woolen yarn be brushed so as to provide a fuzzy surface, it affords a better receptacle for the saponaceous substance. I have found artificial fur, consisting of a cotton backing with a pile of wool, very efficient for my purpose.

The material 3 may be cemented or otherwise affixed to the member 1, leaving the fuzzy surface outermost, of course.

The soap or saponaceous substance 5 is incorporated into the fabric 3 in any suitable manner, so as to thoroughly permeate the same to form a practically homogenous mass therewith and before lathering assumes practically a cake-like character so as to be a practically integral part of the fabric. 100 Any suitable method of permeating the fabric with the soap may be employed.

I have obtained excellent results by interposing between the fabric member 3 and the backing member 1 some padding material 105 6, as shown in Fig. 3 which is more or less porous and at the same time has such a degree of elasticity as to permit of its being compressed more or less when the fabric 3' is pressed against the face, thereby expelling 110 the soap water and air which may be in the pores of the said elastic porous member,

through the fabric, and sucking this mixture back through the fabric when the pressure against the face is relieved or removed. For this purpose I sometimes employ a sheet of soft rubber as seen at 6 in Figure 3; a piece of approximately one-quarter of an inch thick serves admirably.

The sheet of porous elastic material may be held in place upon the back member in any suitable way. The fabric may be secured to the sponge in any suitable manner, as for instance by an adhesive.

The mode of use and the efficiency of the device is the same, regardless of the form of the embodiment of the generic idea, and, in use, the soaped member is dipped in water, and then the face rubbed vigorously and the result will be a heavy lather and an easy shave.

Importance is attached to the elongated form of the applicator as well as its flat rubbing surface whereby I am enabled to apply the lather quicker and better and without having to place the hand in the lather.

From the above it will be obvious that I have devised a simple, very efficient device for the purposes named, and one that can be placed upon the market at trifling cost, thus placing it in the hands of everybody and providing a most sanitary method of applying lather to the face of the person, and while the structural embodiments of the invention as herein disclosed are what I, at the present time consider preferable I do not intend to restrict myself to the details of construction shown and described, but re-

serve the right to make such changes, variations and modifications as come properly within the scope of the protection prayed.

Whether the fabric as applied to the face be round or square makes but little difference, but a practically elongated flat surface for contact with the face is preferable, in many instances, as it affords a good "rubber" by which the lather may be readily and easily rubbed into the beard.

When impregnated all that it is necessary to do is to dip the fabric portion in water and rub the face, when, in one operation, a copious lather is produced, well rubbed into the beard and distributed.

What is claimed as new is:—

1. A lathering device comprising a thin elongated back member, a strip of fibrous fabric permanently adhesively secured thereon near one end thereof, said fabric being permeated with a soluble saponaceous compound forming a substantially permanent constituent thereof.

2. A lathering device comprising a flat backing of elongated form, an elastic porous pad permanently secured adhesively to said backing, and a fibrous fabric covering arranged over said pad, said covering being permeated with a soluble saponaceous substance retained within the fibres of said fabric to form a constituent thereof for application to the face and to be rubbed in to produce a lather.

In testimony whereof I affix my signature.

FREDERICK W. BACORN.
